UNITED STATES PATENT OFFICE.

GEORGE WINSTON, OF CHICAGO, ILLINOIS.

FURNACE.

SPECIFICATION forming part of Letters Patent No. 739,966, dated September 29, 1903.

Application filed May 22, 1903. Serial No. 158,249. (No model.)

To all whom it may concern:

Be it known that I, GEORGE WINSTON, a citizen of the United States of America, and a resident of Chicago, Cook county, Illinois, have invented a certain new and useful Improvement in Furnaces, of which the following is a specification.

Prior to my invention blast-furnaces have always been constructed in such manner that the explosions, which are an unavoidable incident to the operation of such furnaces, have resulted very often in the escape of flying fragments of ore from the top of the furnace and often in a consequent injury to persons and property. My improved furnace is, however, so constructed and designed as to render it impossible for fragments of ore or other missiles to escape from the top of the furnace when the explosions occur, the construction being such that while the gases, dust, &c., are free to escape, and thereby relieve the sudden pressure, the escaping fragments of ore or other materials are received by pipes or flues leading from the explosion-doors at the top of the furnace to points near the ground. With this arrangement the fragments of ore and other debris can be collected and discharged into cars or other receptacles and there is no danger of injury to either persons or property, all as will hereinafter more fully appear.

In the accompanying drawings, Figure 1 is a side elevation of a furnace constructed in accordance with my invention, the upper portion of the furnace and also one of the flues or chutes for collecting the fragments of ore or debris of the explosions being shown in section. Fig. 2 is a view of another side of the furnace shown in Fig. 1. Fig. 3 is a horizontal cross-section on line 3-3 in Fig. 2. Fig. 4 is an enlarged detail sectional view of one of the explosion-doors and adjacent parts.

As thus illustrated my invention may comprise a furnace-body A of any suitable known or approved character. The cast-house B and also the dust-catcher C can be of any suitable character. In accordance with the usual practice the top of the furnace can be provided with a hopper D, adapted to receive the ore, and also with a cone-shaped spreader E for controlling the admission of ore to the

furnace. Preferably, however, and in order to relieve the pressure occasioned by the explosions, which are usually due to the falling of a mass of incrustation or collected ore from immediately below the spreader E, the top or upper portion of the furnace is provided with swinging explosion-doors F, and each door is inclosed by a hood G, so as to prevent the flying fragments of ore or other missiles from doing harm to persons or nearby property. Each hood is preferably provided with an upper relief-pipe g for the escape of gases or dust and also with a lower discharge flue or pipe g'. As will be observed, each discharge flue or pipe preferably extends downwardly to a point where it communicates with one of the two ultimate or final discharge-flues H and H'. In other words, the discharge flue or pipe H is common to the branch pipes or discharge-flues g', while the flue or pipe H' at the other side of the furnace is common to the other three branch pipes or discharge-flues g'. These discharge flues or chutes H and H' extend downwardly to a point where they may discharge into cars or other receptacles I, and their lower ends are preferably provided with valves h. The said explosion-doors F can be provided with operating-chains f, which preferably lead to the lower end of the flues or discharge-pipes H and H' and which can be employed for opening and closing these doors at will.

With the foregoing construction it will be seen that when an explosion occurs from any of the well-known causes, such as the falling of a mass of collected ore from the upper portion of the furnace, the explosion-doors will at once open under the pressure, and whatever fragments of ore or other debris escape through these doors will be caught by the hoods G. The fragments of ore can then descend and accumulate at the lower ends of the discharge-flues H and H', and at various times these flues can be relieved of their contents by opening the valves h. The pipes or flues g, as previously stated, afford a means of escape for the gases, &c. In this way my improved furnace construction permits of the operation of the blast-furnace without any danger of the explosions causing injury to persons or property. Furthermore, the ar-

angement prevents any loss of ore, whatever ore escapes at the top being collected and retained where it is available for use, if desired.

What I claim as my invention is—

- 5 1. A furnace constructed at its top with explosion-openings, hoods arranged over said explosion-openings, a dust-catcher suitably connected with the upper portion of said furnace and discharge-flues independent of said 50
- 10 dust-catcher and leading downwardly from these hoods to points below.
- 15 2. A furnace provided at its top with an explosion-opening, a hood arranged over said opening, a dust-catcher suitably connected with the upper portion of said furnace and a discharge-flue independent of said dust-catcher and leading downwardly from said hood to a point below.
- 20 3. A furnace provided at its top with a plurality of explosion-doors, hoods arranged over said explosion-doors, and discharge-flues leading downwardly from said hoods to suitable points below.
- 25 4. A blast-furnace having its top provided with a plurality of swinging explosion-doors, hoods arranged over said doors, an outlet-flue leading upwardly from each hood, and discharge-flues connected with said hoods and leading downwardly to suitable points 75
- 30 5. A blast-furnace having its top provided with a swinging explosion-door, a hood arranged over said door, an outlet-flue leading upwardly from said hood, and a discharge-flue connected with said hood and leading downwardly to a suitable point below.
- 35 6. A blast-furnace having its top provided with a plurality of explosion-doors, a hood arranged over each said door, the hoods and doors being arranged in a group at each side of the furnace, an outlet-flue rising from each hood, a plurality of discharge-flues each having its upper end connected with a group of said hoods, and a valve device for the lower 80
- 40 45 end of each discharge-flue.

7. A blast-furnace having its top provided with a plurality of explosion-openings, hoods arranged over said openings, relief-pipes leading upwardly from said hoods, discharge-flues leading downwardly from said hoods, and a dust-catcher independent of said discharge-flues and suitably connected with the upper portion of said furnace. 50

8. A blast-furnace having its top provided with a plurality of explosion-doors, suitable connections for operating said doors, hoods arranged over said doors, relief-pipes leading upwardly from said hoods, discharge-flues leading downwardly from said hoods, and a dust-catcher suitably connected with said furnace. 55

9. A blast-furnace having its top provided with a plurality of explosion-doors, hoods arranged over said doors, means for operating said doors, relief-pipes in said hoods, discharge-flues leading downwardly from said hoods, valve devices for controlling the lower ends of said flues, and a dust-catcher suitably connected with the upper portion of said furnace. 60

10. A blast-furnace having its top portion provided with a plurality of explosion-doors arranged in groups at each side of the furnace, hoods arranged over said doors, two downwardly-extending discharge-flues, each connected at its upper end with a group of said hoods, relief-pipes connected with said hoods, and a dust-catcher suitably connected with said furnace. 75

11. A blast-furnace having its upper portion provided with an explosion-door, and an inclosure arranged over said door and provided with a downwardly-extending passage. 80

Signed by me at Chicago, Cook county, Illinois, this 21st day of April, 1903.

GEORGE WINSTON.
